IMPEDANCE TRANSFORMER

Johannes Marinus van Hofweegen and Maximiliaan Julius Otto Strutt, Eindhoven, Netherlands, assignors, by mesne assignments, to Hartford National Bank and Trust Company, Hartford, Conn., as trustee

Application May 9, 1946, Serial No. 668,544
In the Netherlands June 3, 1941

Section 1, Public Law 690, August 8, 1946
Patent expires June 3, 1961

4 Claims. (Cl. 178—44)

1

The invention relates to impedance transformers and, more particularly, to such transformers wherein the impedance to be transformed is connected to the input terminals of a transmission line and the transformed impedance appears at the output terminals of this transmission line. Impedance transformers are frequently used in ultra-high frequency applications, for example where the impedance of a consuming apparatus of ultra-high frequency electrical oscillations has to be adapted to the source of energy. It is also often desired, for example for measuring purposes or in neutralisation systems, to have at one's disposal very small adjustable capacities and inductances of exactly known values. In such cases use may also advantageously be made of an impedance transformer, in which event an impedance whose value is larger or smaller is connected to the one side of the transformer whereas the desired smaller or higher impedance occurs on the other side of the impedance transformer. In this case it is frequently desirable that the ratio of transformation be determinable beforehand as exactly as possible while, in addition, it should be independent of the value of the impedance to be transformed.

The invention has for its object to provide an impedance transformer whose ratio of transformation can be adjusted beforehand at any desired real value. According to the invention, this is achieved by providing in series with and parallel to the transmission line either on the input side or on the output side such impedances that, when the impedance to be transformed is short-circuited, the impedance measured between the output terminals for the operating frequency is equal to zero or at least is a minimum and, when the impedance to be transformed is switched out of circuit, is infinitely high or at least is a maximum. In this case an impedance is measured across the output terminals which is higher than that which is connected to the input terminals if the series impedance is located, with respect to the parallel impedance, on the side of the input terminals of the transmission line whereas at the output terminals of the transmission line an impedance is measured which is smaller than that which is connected to the input terminals, if the series impedance is located, with respect to the parallel impedance, on the side of the output terminals of the transmission line. The series and/or parallel impedance themselves are preferably constituted by tunable transmission lines.

The invention will be explained more fully with

2

reference to the following description and drawing wherein Figs. 1 and 2 diagrammatically represent impedance transformers according to the invention whilst Figs. 3 and 4 serve to elucidate the calculation and Fig. 5 shows another embodiment of an impedance transformer according to the invention.

Fig. 1 represents a circuit-arrangement according to the invention wherein the impedance Z_e which is to be transformed is connected to the input terminals 1, 2 of a transmission line with the characteristic impedance Z_0 . Impedances Z_s and Z_p are provided, respectively, in series with and parallel to the transmission line on the output side. If the impedances Z_s and Z_p are chosen, in accordance with the invention, in such manner that, when Z_1 is short-circuited, the impedance measured between the output terminals 1, 2 for the operating frequency is equal to zero and, when Z_1 is switched out of circuit, is infinitely high, the impedance Z_t which occurs at the output terminals 3, 4 of the transmission line amounts in this circuit-arrangement, if Z_1 is connected in the ordinary manner, to

$$Z_t = Z_e \times \frac{1}{\cos^2 \beta \times 1} \text{ wherein } \beta = \frac{2\pi}{\lambda}$$

(λ is the wavelength in the conductor of the electric oscillations of operating frequency).

If it is desired to have at one's disposal an adjustable capacity whose maximum value is 0.1 pf., this capacity may be obtained, for example, by taking for Z_s a variable capacity with a maximum value of 20 pf. and to adjust the length of the transmission line in such manner that $\cos^2 \beta_1 = 0.01$ or $\cos \beta_1 = 0.1$. With a wavelength of 50 cms. a length of the transmission line of 11.7 cms is necessary for this purpose, which length may be adjusted beforehand. As may be seen from Fig. 1, the conductor of 10 pf. is connected between the terminals 1 and 2 on the input side of this transmission line. Then the regulable impedance Z_s is provided, for example, in the form of a transmission line, and is adjusted in such manner, that, when the condenser Z_e is short-circuited, an impedance zero is measured between the terminals 3 and 4. Subsequently, the impedance Z_p is connected between the terminals 3 and 4 and, when the condenser Z_e is switched out of circuit, the impedance Z_p is adjusted in such manner that an infinitely high impedance is measured between the terminals 3 and 4. If then the impedance Z_e in the form of the condenser of 10 pf. is connected in the ordinary manner, an impedance which is a hundred times

higher and consequently a capacity which is a hundred times smaller, is observed between the terminals 3 and 4.

With the use of the circuit-arrangement according to Fig. 2 there is measured if the impedances Z'_p and Z_s are adjusted in a manner analogous to that which has been set out above, an impedance Z'_t which is equal to $Z'_1 \cos^2 \beta_1$ and which is consequently always smaller than Z'_1 . It is thus possible to step down the value of an inductance of given value which is connected at the place of Z'_1 in Fig. 2, to a fraction of that value.

If in the circuit-arrangement according to Fig. 1 the impedance to be transformed Z_e is connected to the terminals 3, 4, it is possible to deduce that with a corresponding adjustment of the impedances Z_s and Z_p an impedance is measured between terminals 1 and 2 Z_t which is equal to $Z_1 \cos^2 \beta_1$ wherein consequently the value of the impedance Z_1 is stepped down. If with the circuit-arrangement according to Fig. 2 the places of the impedance to be transformed and of the transformed impedance are interchanged in a similar manner, there is measured between the terminals 1 and 2 an impedance Z'_t which is equal to

$$Z'_t = \frac{1}{\cos^2 \beta_1}$$

and wherein consequently the value of the impedance is stepped up.

According to the circuit-arrangement of Fig. 1 it is shown, on the basis of the following calculation, that under the given conditions the impedance occurring at the terminals 3 and 4 is actually equal to

$$Z_e \times \frac{1}{\cos^2 \beta_1}$$

As is well-known, the impedance of the transmission line, which is closed on one side by an impedance Z_1 , is represented by

$$Z_e = \frac{Z_e + jZ_0 \operatorname{tg} \beta_1}{1 + j \frac{Z_e}{Z_0} \operatorname{tg} \beta_1} \quad (1)$$

If the transmission line is short-circuited on the one side, the impedance at the other end amounts to

$$Z_k = jZ_0 \operatorname{tg} \beta_1 \quad (2)$$

and, if the transmission line is open at one end, the impedance at the other end is

$$Z_\infty = -jZ_0 \operatorname{cotg} \beta_1 \quad (3)$$

If now the impedance Z_s is incorporated in the transmission line which is short-circuited on the output side 1, 2 the impedance Z_1 between the terminals 3 and 4 is $Z_1 = Z_k + Z_s + jZ_0 \operatorname{tg} \beta_1$. It follows therefrom for Z_s , if Z_1 must be equal to 0, that

$$Z_s = -jZ_0 \operatorname{tg} \beta_1 \quad (4)$$

If, after this impedance Z_s has been provided at the place indicated in Fig. 1, also the impedance Z_p is provided and the connection between the terminals 1 and 2 is removed, the reciprocal value of the impedance Z_2 which occurs between the terminals 3 and 4 is

$$\frac{1}{Z_2} = \frac{1}{Z_p} + \frac{1}{Z_s + Z_\infty} \quad (5)$$

According to the invention, Z_p is adjusted in

such manner that under these conditions $Z_2 = \infty$ and therefor

$$\frac{1}{Z_2} = 0$$

If the values obtained for Z_s and Z_∞ according to the Formulas 3 and 4 are inserted in the Formula 5 and if

$$\frac{1}{Z_2}$$

is supported to be equal to zero, it follows therefrom that

$$Z_p = jZ_0 \times \frac{1}{\sin \beta_1 \cos \beta_1} \quad (6)$$

In Fig. 1 the reciprocal value

$$\frac{1}{Z_t}$$

of the impedance Z_t which is measured between the terminals 3 and 4 is, if Z_e is switched into circuit, equal to

$$\frac{1}{Z_p} + \frac{1}{Z_s + Z_t}$$

After substitution of the values found for Z'_1 (1), Z_s (4) and Z_p (6) and after a few operations it is found that:

$$\frac{1}{Z_t} = \frac{\cos^2 \beta_1 (1 + j \frac{Z_s}{Z_0} \operatorname{tg} \beta_1)}{Z_s} + \frac{\sin \beta_1 \cos \beta_1}{jZ_0} = \frac{\cos^2 \beta_1}{Z_1}$$

and therefore

$$Z_t = Z_1 \times \frac{1}{\cos^2 \beta_1}$$

In a similar manner it is possible to deduce the ratio of transformation given for the circuit-arrangement according to Fig. 2, as well as the ratios of transformation which occur when the places of the impedance to be transformed and of the transformed impedance are interchanged. Furthermore, it appears from further calculations that, if further impedances are located in series with or parallel to the impedance to be transformed, these impedances do not affect the transformation if care is taken to ensure that upon adjusting the impedances Z_s and Z_p exclusively the impedance to be transformed only in short-circuited and switched out-of-circuit respectively.

The impedances Z_s and Z_p are formed in practice by transmission lines of adjustable electrical length as shown in Fig. 5; in which Z_s and Z_p are transmission lines whose respective electrical lengths are made adjustable by means of short-circuiting bars 5 and 6, respectively.

What we claim is:

1. An impedance transformer comprising a transmission line of given length determined by a given transformation ratio having input and output terminals, a variable impedance in series with said transmission line, and a variable impedance in parallel with said line, said series and parallel impedances each being adjustable within a given range of values at which within a predetermined range of operating frequencies the impedance of the line viewed from the output terminals is a minimum when the line is short-circuited at the input terminals and a maximum when the line is open-circuited at the input terminals whereby the line reflects at the output terminals when an impedance of given value is connected across the input terminals, a trans-

formed value of said impedance across the input terminals.

2. An impedance transformer comprising a transmission line of given length determined by a given transformation ratio having input and output terminals, a variable impedance in series with said transmission line, and a variable impedance in parallel with said transmission line, said series impedance being connected in said transmission line between said parallel impedance and said input terminals, said series and parallel impedances each being adjustable within a given range of values at which within a predetermined range of operating frequencies the impedance of the line viewed from the output terminals is a minimum when the line is short-circuited at the input terminals and a maximum when the line is open-circuited at the input terminals whereby the line reflects at the output terminals when an impedance of given value is connected across the input terminals.

3. An impedance transformer comprising a transmission line of given length determined by a given transformation ratio having input and output terminals, a variable impedance in parallel with said transmission line, said series impedance being connected in said transmission line between said parallel impedance and said output terminals, said series and parallel impedances each being adjustable within a given range of values at which within a predetermined range of operating frequencies the impedance of the line viewed from the output terminals is a minimum when the line is short-circuited at the input terminals.

put terminals and a maximum when the line is open-circuited at the input terminals whereby the line reflects at the output terminals when an impedance of given value is connected across the input terminals a transformed value of said impedance across the input terminals.

4. An impedance transformer comprising a transmission line of given length determined by a given transformation ratio having input and output terminals, a first tunable transmission line in series with said transmission line, and a second tunable transmission line in parallel with said transmission line, said first and second tunable transmission lines being each adjustable to provide impedances each having a given range of values at which within a predetermined range of operating frequencies the impedance of the line viewed from the output terminals is a minimum when the line is short-circuited at the input terminals and a maximum when the line is open-circuited at the input terminals whereby the line reflects at the output terminals when an impedance of given value is connected across the input terminals a transformed value of said impedance across the input terminals.
